US0D1088859S

(12) **United States Design Patent** (10) **Patent No.:** **US D1,088,859 S**
(45) **Date of Patent:** **** Aug. 19, 2025**

(54) **BOX**

(71) Applicant: **Pratt Corrugated Holdings, Inc.**,
Brookhaven, GA (US)

(72) Inventor: **Randy Ball**, Peachtree City, GA (US)

(73) Assignee: **Pratt Corrugated Holdings, Inc.**,
Brookhaven, GA (US)

(**) Term: **15 Years**

(21) Appl. No.: **29/967,735**

(22) Filed: **Oct. 11, 2024**

Related U.S. Application Data

(63) Continuation of application No. 29/943,344, filed on May 21, 2024, now Pat. No. Des. 1,052,397, which is a continuation of application No. 29/825,994, filed on Feb. 8, 2022, now Pat. No. Des. 1,056,702.

CLAIM

The ornamental design for a box, as shown and described.

DESCRIPTION

FIG. 1 is a perspective view of a box.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof; and,

FIG. 7 is a bottom plan view thereof.

The dash-dash broken lines depict portions of the box that form no part of the claimed design, while the dot-dash broken lines depict unclaimed boundaries of the claimed design.

1 Claim, 7 Drawing Sheets
